Dr. W. W. Compton

ATTORNEYS

UNITED STATES PATENT OFFICE

ADIEL V. DODGE, OF SOUTH BEND, INDIANA, ASSIGNOR TO BENDIX BRAKE COMPANY,
A CORPORATION OF ILLINOIS

BRAKE MECHANISM

Original application filed October 8, 1924, Serial No. 742,282. Divided and this application filed May 16, 1928. Serial No. 278,156.

My invention relates to improvements in brake mechanism and is illustrated as embodied in internal brake mechanism particularly adapted for use on a motor vehicle.

5 The invention is illustrated as comprising a pair of pivotally connected brake shoes provided with novel operating and supporting mechanism including a floating wedge riding over the face of a cam to be urged against the shoes to force them against the rotatable member and swinging linkage which carries the pivotal connection between the shoes whereby one shoe serves to exercise a servo action upon the other shoe depending upon 10 the direction of rotation of the drum.

Other advantages and meritorious features 15 of my improved construction will appear from the following specification appended claims and accompanying drawing, where-

20 in—

Fig. 1 is a vertical sectional view through a brake drum showing the brake shoes and applying means in elevation.

Fig. 2 is a vertical section through the link support for the brake.

This application is a division of my application, Ser. No. 742,282, filed October 8, 1924, now patent No. 1,705,855, dated March 19, 1929.

30 The brake drum is indicated as 10. Two substantially inflexible brake shoes 12 and 16 are arranged within the drum. These shoes are pivotally articulated as at 14. The opposite ends 22 and 26 of the shoes are slotted as 35 at 24 and 28 and a stationary anchor carried by the backing plate 58 is mounted within each slot. Anchor 18 is mounted within the slot 24 to anchor the shoes when the drum is rotating in a counter-clockwise direction and anchor 20 is located within the slot 28 to anchor the shoes when the drum is rotating in a clockwise direction.

The pivotally connected ends of the shoes are mounted upon a pivot 14 carried by a 40 swinging link 54 pivoted for swinging movement at 56.

A stop adjustment is shown at 62 and a return spring is indicated as 52. Operating mechanism is provided to spread the shoes 45 apart and this operating mechanism is capa-

ble of floating to adapt itself to both the operative and the inoperative positions of the brake.

The operating mechanism comprises a pull rod 50 pivoted at 48 to a link 46 to which is 55 connected a shaft 44 journaled in the backing plate and carrying a cam 42 to rotate therewith. This cam 42 engages for operation a wedge 34 pivoted at 36 to a link 38 journaled upon a pivot 40 in the backing plate so that 60 actuation of the cam moves the wedge between the ends of the shoes 12 and 16. This wedge directly engages bearing rollers 30 and 32 carried by the extreme ends of the 65 shoes 12 and 16 respectively.

In the operation of the device when the cam is actuated to apply the shoes to the drum, if the drum is rotating in a clockwise direction, shoe 16 anchors upon the anchor 20 and the shoe 12 is urged against the drum by the 70 wedge 34 and in turn exerts a servo action upon the shoe 16. The converse is true if the drum is rotating in the opposite direction.

What I claim is:

1. Brake mechanism comprising, in combination with a rotatable brake drum, substantially inflexible brake shoes directly pivoted together and arranged within the drum having spaced apart free separable slotted ends, an anchor arranged within each slotted end to anchor the shoes when the drum is rotating in the direction to bring either shoe against its anchor while permitting the said shoe to travel over the anchor when the drum is turning in the opposite direction to apply 75 the anchored shoe to the drum, a wedge member pivotally supported at the free end of a pivotally mounted link, operating mechanism comprising a rotatably supported involute cam engaging the pivoted end of said 80 wedge member to urge it between the shoes to spread said shoes against the drum, and a swinging link supporting the pivotal connection between said shoes.

2. Brake mechanism comprising, in combination with a rotatable drum, friction means having separable ends arranged within the drum, an anchorage positioned in proximity to the separable ends of said friction means to anchor said means in either direc- 95 100

tion of rotation of the drum engaging one end of said friction means when the drum is rotating in one direction and the other end of said means when the drum is rotating in the opposite direction a link having one end mounted upon a fixed pivot for swinging movement thereover and having a wedge pivotally swung from its opposite and free end, said wedge extending between the separable ends of the friction means, and a cam disposed to be operated to exert a thrust upon said link to urge the wedge between the separable ends of the friction means to apply said means to the drum.

10 15 In testimony whereof, I, ADIEL Y. DODGE, sign this specification.

ADIEL Y. DODGE.
